M. LOBBENBERG

BACK LACING OF BUST SUPPORTERS AND THE LIKE

Filed Sept. 11, 1924

Max Lobbenberg
Inventor:
By Paul H. Helling
Attest:

UNITED STATES PATENT OFFICE.

MAX LOBBENBERG, OF COLOGNE-LINDENTAL, GERMANY.

BACK LACINGS OF BUST SUPPORTERS AND THE LIKE.

Application filed September 11, 1924. Serial No. 737,082.

To all whom it may concern:

Be it known that I, MAX LOBBENBERG, a citizen of Germany, residing at Cologne-Lindenthal, Rhenish Prussia, Germany, have invented certain new and useful Improvements in Back Lacings of Bust Supporters and the like; and I do hereby declare the following to be a full, clear, and exact description of the invention, such as will enable others skilled in the art to which it appertains to make and use the same.

This invention relates to bust supporters, corsets and the like having a continuous closed front portion and a lacing down the back.

In putting on garments of this kind the back lacing must first be widened for allowing the garment to be drawn over head and shoulders and afterward be tightened again for narrowing the garment to obtain the proper fit on the body. If, as usual, this has to be done by the wearer herself, it is often very difficult for the same to find among the numerous zigzag paths of the lace the proper oppositely disposed portions which serve as tightening loops for the parts of the lacing lying above and below said loops. Even if these loops are previously loosened to a considerable extent or drawn out of the lacing, inconveniences frequently arise inasmuch as the long down-hanging loops become entangled in groping for them or become shifted between the body and the garment. Besides, in this case the laces must be very long so that after the tightening and binding of the lacing, the loops give even more cause for an entanglement of the laces owing to their length, thereby entailing a new cause for further inconveniences in undressing.

My invention has for its object to provide a back lacing for garments of the kind stated with which the portions of the lace designed to form the loops for tightening the lacing, carry finding members shiftable on the lace and adapted to be easily felt by the user's fingers, so as to allow of the tightening loops being readily found and sorted out from among the other windings of the lacing. Owing to the arrangement of the finding members, the finding of the tightened loops will be as easy in the widened as in the contracted condition of the garment, and the lace may be much shorter than in the well-known lacings, thereby re-

ducing the danger of the laces becoming entangled in putting on the garment.

Another object of the invention is to provide an embodiment still further facilitating the handling of the lacing by providing the eyelet lacing edges of the back sections at the outer side with covering flaps having each a pair of guiding eyelets for the passage therethrough of the tightening loops, so that in groping for the flaps with the fingers the tightening loops may be readily found.

The invention will now be described with reference to the accompanying drawings, in which Fig. 1 is a partial rear elevation of a bust supporter in widened condition provided with a lacing according to the invention. Fig. 2 is a similar elevation of a modified form of the back lacing, and Fig. 3 is a section along the line III—III of Fig. 2.

Referring first to Fig. 1, the two back sections 1 of the bust supporter are provided at their lacing edges 2 with the ordinary row of eyelets 3 through which the lace 4 is drawn in a double zigzag winding in the usual way. The two ends of the lace are connected with each other for instance by knotting as at 5.

Two of the zigzag paths of the lace which lie in the middle are drawn out in a well known manner so as to form pulling or tightening loops 6. The portions of the lace constituting the loops pass each through a metallic ring 7. These rings will be readily felt by the fingers in groping for the lacing, thereby indicating the tightening loops in a quick and secure manner to the wearer. Owing to the fact that the finding rings are shiftable on the lace, they will not interfere in any way with the proper tightening of the lacing.

The metal finding ring may be replaced by a wooden pearl, a shiftable ring of woven material, a tassel, or the like.

The back-lacing of the bust supporter shown in Figs. 2 and 3 is of the same kind as that shown in Fig. 1, but in addition thereto the eyeleted lacing edges 2 are covered at their outer sides by flaps 8. With the embodiment shown, these flaps are formed by the edges of the back sections 1 of the bust supporter, while the lacing edges 2 consist of separate strips of fabric stitched to the edge portions of the back sections 1. As a matter of course, the eyeleted lacing edges 2 may as

well be formed by the back sections 1 in the usual manner, while the covering flaps 8 may consist of special strips of fabric to be stitched to the outer side of the edge portions 5 of the back sections 1.

The covering flaps 8 are provided each with a pair of guiding eyelets 9 spaced from each other and lying somewhat below the middle of the garment. The portions of the lace 4 drawn out as in Fig. 1 to form the tightening loops 6 are passed through the eyelets 9 of the covering flaps 8 and are likewise provided with a shiftable finding member such as the metal ring 7. The tightening loops 6 are thus brought entirely out of range of the other windings of the lacing, thereby greatly facilitating the finding of the loops in handling the lacing and securely protecting them from becoming entangled with the other windings of the lacing or with other garments. The eyelets 9 of the covering flaps 8 also determine the place at which the tightening loops 6 have to be drawn out, this being very convenient for unskilled wearers.

25 What I claim is—

1. In combination with a bust supporter or the like having a back-lacing comprising

eyeleted edges and a lace drawn through the eyelets, tightening loops formed by certain portions of the lace, and finding members 30 shiftable on the portions constituting the said loops.

2. In combination with a bust supporter or the like having a back-lacing comprising eyeleted edges and a lace drawn through the eyelets, tightening loops formed by certain portions of the lace, and metal finding rings 35 shiftable on the portions constituting said loops.

3. In combination with a bust supporter 40 or the like having a back-lacing comprising eyeleted edges at the back sections and a lace drawn through the eyelets, tightening loops formed by certain portions of the lace, flaps at the edge portions of the back sections designed to cover the eyeleted lacing edges at 45 their outer sides, a pair of guiding eyelets in each flap for the passage therethrough of the tightening loops, and finding members shiftable on the portions of the lace constituting 50 the said loops.

In testimony whereof I have signed my name to this specification.

MAX LOBBENBERG.
